FIG.1

FIG.5

FIGURE 1 is a perspective view of a hair brush and comb combination embodying my new design, and illustrating the comb in the partial operating position;

The opposite side of the comb has substantially the same appearance as the side shown in FIGURE 1.

It is to be understood that the broken lines representing the bristles cover the entire area indicated by dot-dash lines.

The dominant features of my design reside in the portions shown in full lines.

I claim:

The ornamental design for a hair brush and comb combination, as shown and described.
